W. R. SLAPPEY

WINDOW SASH RETAINING ARRANGEMENT

Filed April 3, 1923

Fig. 1.

UNITED STATES PATENT OFFICE.

WILLIAM R. SLAPPEY, OF JACKSONVILLE, FLORIDA.

WINDOW-SASH-RETAINING ARRANGEMENT.

Application filed April 3, 1923. Serial No. 629,661.

To all whom it may concern:

Be it known that I, WILLIAM R. SLAPPEY, a citizen of the United States, residing at Jacksonville, in the county of Duval and State of Florida, have invented certain new and useful Improvements in Window-Sash-Retaining Arrangements, of which the following is a specification.

This invention relates to improvements in window sash constructions.

The primary object of this invention is to provide a novel arrangement for maintaining window sashes in their most effective relation with respect to the casings in which they are movably positioned, so that the same will be prevented from rattling and may be conveniently operated.

A further object of this invention is the provision of an improved trackway arrangement, for window retainers such as is illustrated in my copending application, Serial #565,593, filed June 3, 1922.

Other objects and advantages of this invention will be apparent during the course of the following detailed description.

In the accompanying drawing, forming a part of this specification, and wherein similar reference characters designate corresponding parts throughout the several views:

Figure 1 is a front elevation, partly in section, of a window sash and its supporting frame, showing the improved sash supporting and retaining arrangement as used in connection therewith.

Figure 2 is a fragmentary edge elevation of the sash or closure member showing the manner in which the novel retaining member is disposed therein in cooperative manner therewith.

Figure 3 is an enlarged fragmentary cross sectional view, showing cooperating details of this invention.

Figure 4 is a perspective view of a novel sash retaining member as used in connection with this invention.

In the drawing, wherein for the purpose of illustration is shown but the preferred embodiment of this invention, the letter A may designate a sliding sash of any approved type, movably mounted within its supporting frame B, and having the improved retaining means C associated therewith, so that the same may be supported in non-rattling and easy operating position within the frame B.

The sash A may be of any approved type and preferably includes the pane 10 encased within a supporting frame 11, the side frame pieces 12 of which are recessed as at 13 and 14, inwardly from their outside edges and are provided with the longitudinal V-shaped grooves 15 extending inwardly of the outside faces or edges thereof from top to bottom of the sash A, and in intersecting relation with the recesses 13 and 14. The recesses 13 and 14 are, of course, provided for receiving the sash retaining members 16 of the sash mounting means C, as will be subsequently described.

The window frame B may be of any approved construction, preferably including a sill 17, and the vertical stiles 20 intermediate which the sash A slides. The stiles 20 may of course be provided with retaining strips for slidably supporting a single or double sash, and may include the inside and outside stop beads 21 and 22 respectively, of strip formation, and the intermediate or parting bead 23. These beads may be of the conventional construction, and provide ways intermediate the same projecting from the stiles 20 for slidable disposition of the side portions of the sash A.

Referring to the improved mounting means C, the same preferably includes a trackway 25, which may be of copper or any approved material, the same preferably being substantially V-shaped in cross section and at the base thereof being provided with side lugs 26 apertured for receiving retaining elements 27, whereby said trackway 25 may be attached within the ways intermediate the stop and parting beads. It is preferred that the outer surface 29 of the trackway 25 be convexed, and the trackways 25 are so positioned within the ways intermediate the parting and stop beads that the center line thereof is disposed nearer to the inside facing surface 30 of the innermost bead than with respect to the facing surface 32 of the outermost bead. This is illustrated in Figure 3 of the drawings, as the distance X is greater than the distance Y, so that as is illustrated in this drawing the trackway 25 intermediate the outside stop bead 21 and the parting bead 23 will be disposed nearer the latter than the former. Similarly the trackway 25 intermediate the parting bead 23 and the inside stop bead 22 will be disposed nearer the latter than the former. The trackway 25 and particularly the con-

convex surface 29 thereof extends outwardly from the outside surface of the stile 20 to which it is attached, for cooperation with the retaining members 16, as will be subsequently described.

Referring to the retaining members 16, the same are in the main constructed after the retaining members illustrated in my copending application above referred to and 10 include strips of material 35 bent substantially midway of their ends to provide relatively straight leg portions 36 and 37 upon each, and in substantially V-shaped relation. The leg 36 of each retaining member 16 is 15 preferably provided with a pair of openings 38 and 39 therein respectively disposed adjacent the free end and connecting end thereof adapted to receive attaching elements such as screws, whereby the same may be positioned within the recesses 13 and 14 of the sash A. The leg portion 37 of each member 16 is preferably bifurcated at its free end to provide arm portions 40 and 41 rolled at their free ends to provide aligning openings 20 for receiving a pin 42, upon which a steel 25 roller 43 is rotatably mounted intermediate the arms 40 and 41. The roller 43 is unlike the roller illustrated in my copending application above referred to, and is preferably 30 provided with an annular groove 45, which is concaved in cross section, and adapted for substantially snugly receiving the convex surface 29 of a trackway 25. Thus, it is obvious that by the provision of the annular 35 groove 45, the roller 43 provides flanges which may engage the sides of the trackways 25. It is preferred that the leg portion 37 of each member 16 be provided with an opening 47 adjacent its connecting end, which when 40 the portions 36 and 37 are in substantially doubled relation will align with the opening 39 in the former. Similarly, it is preferred that the slot 49 intermediate the arms 40 and 45 41 be of sufficient depth to expose the opening 38 of leg 36 when the latter is bent proximate the leg 37. This is in accordance with the easy attaching feature heretofore described in my copending application above referred to.

50 The members 16 are preferably assembled in the upper and lower recesses 13 and 14 of the sash A at the side strips 12 thereof, so that the leg portions 36 thereof are rigidly secured against the strips 12 with the arm portions 37 upstanding and downstanding in resilient manner from the upper and lower recesses 13 and 14 respectively, so that the rollers 43 are normally urged into engagement with the trackways 25. Incident to the 55 fact that the trackways 25 have been eccentrically positioned with respect to the facing surfaces 30 and 32 of the retaining beads intermediate which the sash slides, it is obvious that the rollers 43 will engage the trackways 25 so that the inside flanges thereof

more firmly engage the inside surfaces of the trackways than the outer flanges of said rollers, substantially as is illustrated in Figure 3 of the drawing, and which arrangement will resiliently maintain the side pieces 12 of the 70 sash frame 11 into engagement with the inside surfaces 30 of the inside retaining bead against which the same rests, as to prevent any liability of rattling of the window incident to wind pressure from the outside of the building in which the window construction is provided. The retaining members 16 are of course accurately positioned upon the frame 11 of the sash A, so that when in position intermediate the stop and parting beads, the resilient arm portions 37 of said retaining members 16 will be slightly sprung to resiliently urge the sash A against the innermost stop or parting beads, and after the manner illustrated in Figure 3 of the drawing. Incident to the provision of the longitudinal V-shaped grooves 15 in the side pieces of the sash frame, the sash may compactly and accurately fit within the window frame B, against liability of any binding 80 action.

From the foregoing description of this invention, it is apparent that sash retaining means has been provided for window constructions, by which the sash may be effectively retained in non-rattling and non-vibratory position in resilient manner, so that the window sash may be easily and conveniently operated and retained in a predetermined position within the window casing, either open or closed.

Various changes in the shape, size and arrangement of parts may be made to the form of invention herein shown and described, without departing from the spirit 105 of the invention or the scope of the claims.

I claim:

1. In combination with a casing including inner and outer strips, of a sash for sliding in said casing intermediate said strips, a trackway carried by said casing intermediate said strips, and resilient members supported by said sash engaging said trackway a cam action being set up between the resilient members and trackway for 110 laterally urging said sash into resilient and yieldable engagement with the inside strip.

2. In combination with a casing having stop beads extending laterally of a stile thereof, and a sash for sliding in said casing intermediate said stop beads, of a trackway attached to said stile intermediate said stop beads including a convexly arched portion extending outwardly from the stile, the center line of which trackway is 115 disposed nearer to a facing surface of one of said stop beads than with respect to the other of said stop beads, and means resiliently supported by said sash at the stile facing edges thereof adapted to engage said 120 trackway.

trackway, a cam action being set up between the resiliently supported means and arcuate portion of the trackway so that the means is sprung to yieldably urge said sash into engagement with the side of the stop bead which is nearest to the center line of said trackway.

3. In a device of the class described, the combination with a casing including retaining strips and a sash for sliding therebetween, of cam means supported by the casing, and means carried by the side edges of the sash and engaging the cam means to force said sash laterally into engagement with a side of one of the retaining strips.

4. In combination with a window casing including side stiles having inside and outside stop beads and a parting bead extending laterally therefrom to provide vertical ways and sashes for sliding within said ways, of trackways attached to said stiles within said ways substantially V-shaped in cross section and provided with convexed outer track

surfaces, said trackways being parallel with respect to said beads and so distanced with respect thereto that the center line of the trackways are disposed nearer to the facing surfaces of the inside adjacent beads than with respect to the facing surfaces of the outside adjacent beads, said sash having recesses in the outside stile facing edges thereof, and having said outside surfaces thereof recessed in V-shaped manner intersecting said recesses, and substantially V-shaped retaining members attached in said recesses and including resilient arms provided with annularly grooved rollers rotatably supported on the ends thereof normally urged by said resilient arms into overlapping relation with the convex surface of said trackways whereby the resilient arms will be slightly sprung by engagement with said trackways to yieldably urge the sash into engagement with the nearest facing surface of the innermost beads.

WILLIAM R. SLAPPEY
